MUFFLER

Robert A. Heath, Jackson, Mich., assignor, by mesne assignments, to Walker Manufacturing Company, Racine, Wis., a corporation of Delaware

Application August 14, 1957, Serial No. 47,359

Term of patent 14 years

(Cl. D14—6)

Fig. 1 is a side elevation of a muffler showing my new design;

Fig. 2 is a section taken along the line 2—2 of Fig. 1;
Fig. 3 is a plan view of the muffler shown in Fig. 1; and
Fig. 4 is an enlarged section taken along the line 4—4 of
Fig. 3.

The dominant feature of my design resides in the full line portion of the drawing.

I claim:

The ornamental design for a muffler, as shown and described.
